CLAIM

The ornamental design for a teardrop-shaped ornamentation, as shown and described.

DESCRIPTION

FIG. 1 is a front perspective view of a teardrop ornamentation showing a first exemplary embodiment of my new design;

FIG. 2 is a front elevational view of the first exemplary embodiment of my new design of a teardrop ornamentation; FIG. 3 is a rear elevational view of the first exemplary embodiment of my new design of a teardrop ornamentation; FIG. 4 is a right side view of the first exemplary embodiment of my new design of a teardrop ornamentation;

FIG. 5 is a left side view of the first exemplary embodiment of my new design of a teardrop ornamentation;

FIG. 6 is a top plan view of the first exemplary embodiment of my new design of a teardrop ornamentation;

FIG. 7 is a bottom plan view of the first exemplary embodiment of my new design of a teardrop ornamentation; FIG. 8 is a front perspective view of a teardrop ornamentation showing a second exemplary embodiment of my new design;

FIG. 9 is a front perspective view of a teardrop ornamentation showing a third exemplary embodiment of my new design;

FIG. 10 is a front perspective view of a teardrop ornamentation showing a fourth exemplary embodiment of my new design;

FIG. 11 is a front perspective view of a teardrop ornamentation showing a fifth exemplary embodiment of my new design;

FIG. 12 is a front perspective view of a teardrop ornamentation showing a sixth exemplary embodiment of my new design; and,

FIG. 13 is a front perspective view of a teardrop ornamentation showing a seventh exemplary embodiment of my new design.
